UNITED STATES PATENT OFFICE.

JOSEPH E. TYNAN, OF PATERSON, NEW JERSEY.

SPINDLE FOR SPINNING.

SPECIFICATION forming part of Letters Patent No. 408,862, dated August 13, 1889.

Application filed July 14, 1888. Serial No. 279,941. (No model.)

To all whom it may concern:

Be it known that I, JOSEPH E. TYNAN, of Paterson, in the county of Passaic and State of New Jersey, have invented a new and useful Improvement in Spindles for Spinning, of which the following is a specification, reference being had to the accompanying drawings.

My improvement, which is applicable to spindles and bobbins for the spinning of various fibrous materials, is more especially designed for spinning silk.

For spinning silk it is desirable that the spindle should be as light as possible, and that, while the bobbin should be accurately and securely centered upon the spindle, it should be capable of such easy removal therefrom by taking hold of it in the hand with the silk upon it that the grasp of the hand need not injure or disarrange the silk.

The object of my invention is to obtain a spindle possessing the desirable qualities hereinabove mentioned.

I will now proceed to describe my invention with reference to the accompanying drawings, and will afterward point out its novelty in a claim.

Figure 1 represents an elevation of a spindle and bobbin adapted for spinning a doubled thread of silk embodying my invention, showing also a spindle-bolster and bolster-supporting tube, a step, and a flier, all the parts except the spindle being in section. Fig. 2 is a similar view of a spindle and bobbin adapted for the spinning of a single thread.

Similar letters of reference designate corresponding parts in both figures.

Referring first to Fig. 1, A designates the spindle, and B the bobbin.

40 C is the bolster, D the bolster-supporting tube, and I the rail of the spinning-machine in which the said tube is supported, and secured in the usual or any convenient manner.

45 The spindle is represented as having the lower part, which fits the bolster, of cylindrical form, and as having its lower end supported on a step at the bottom of the bore of the bolster-supporting tube D. Above the 50 bolster the spindle is represented as slightly tapered upward, the part which is received

within the upper part of the bobbin being very much smaller than the bore of the bobbin.

E designates a metal sleeve, the upper part 55 of which is fitted and tightly secured upon the portion of the spindle above the bolster and bolster-supporting tube, and the lower part of which is large enough internally to pass loosely and without touching over the 60 exterior of the bolster-supporting tube B, and has a whirl F formed around its bottom. The upper part of this sleeve is conical externally and slightly larger than the upper part a of the bore of the bobbin. This part a of the bore of 65 the bobbin may be of the usual size to fit the ordinary winding-spindle, on which the bobbin may be secured in the usual way for winding the thread upon it; but below this portion the bore of the bobbin is slightly enlarged conically, as shown at c, to fit the conical portion e of the sleeve E, the said conical portion c of the bore being at about the 70 middle of the length of the bobbin, but preferably, as represented, just above the middle. 75 Below this conical portion c the bore of the bobbin is enlarged, that it may pass freely over that portion of the sleeve E which is outside of the bolster-supporting tube. The said lower portion of the said sleeve is cy- 80 lindrical, and the corresponding lower portion of the bore of the bobbin is of a cylindrical form to correspond, but just so slightly larger that while it will not bind upon that portion of the sleeve it may center the bobbin thereon, leaving the bobbin to fit tightly to the upper conical portion e of the said sleeve with the conical portion c of its bore only.

85 The bobbin is held and supported upon the 90 spindle and caused to rotate therewith only by means of the conical portion c of its bore fitting tightly on the conical portion of the sleeve, and it does not touch the spindle itself at any point; and the important feature of 95 this improvement consists in that the part e of the sleeve of the spindle and the corresponding part c of the bore of the bobbin fitted thereto may be made of a taper form much more abrupt than it would be possible 100 to give, without an enormous increase of weight, to a spindle upon which the bobbin

fits directly, and the size of the upper part of which is governed by the size of the preparatory winding-spindle, and it is owing to the bobbin being entirely supported and carried 5 upon this abrupt taper portion of the sleeve that the easy removal of the bobbin from the spindle is provided for.

In the example of the invention represented in Fig. 1, the bolster C has the greater portion 10 of the length of its exterior smaller than the bore of the supporting-tube D, but has a rounded external swell b, which fits said bore in such manner as to provide for the slight oscillation of the bolster and the slight lateral movement in all directions of the lower 15 part of the spindle. Below the said swell b there is interposed between the bolster and the bore of its supporting-tube a conical spiral spring G, the interior of the upper portion 20 of which fits the bolster and the exterior of the lower portion of which fits the supporting-tube. The bolster and the said spring G constitute a bearing for the lower part of the spindle, which is capable of yielding or moving laterally in all directions. By thus providing a laterally-yielding bearing, which will allow the spindle and its load to find its true center of rotation, I am enabled to make the taper of the portions c of the bore of the 25 bobbin and e of the exterior of the sleeve more abrupt than would otherwise permit the bobbin to be retained tightly upon the said sleeve during the rapid rotation of the spindle.

In the example of the invention represented 30 in Fig. 1 the spindle is represented as long

enough to project sufficiently high above the bobbin to receive a flier II, which may be of any well-known or suitable kind.

In the example of my invention represented in Fig. 2, no flier being required, the upper 40 part of the spindle terminates below the top of the sleeve E. In all other respects this example is like that shown in Fig. 1.

A spindle with its sleeve E and whirl F constructed according to my invention, for a 45 bobbin of a given size, does not require to weigh half as much as the lightest spindle now in use for a bobbin of the same size.

In adapting a bobbin to my invention the enlargement of those parts of the bore which 50 are to receive the sleeve F does not impair its capability of being secured in the usual manner to the winding-spindles, as the part a of the bore above the taper middle portion C is left of sufficient length to be properly secured 55 upon the winding-spindle.

What I claim as my invention, and desire to secure by Letters Patent, is—

The combination, with a spinning-spindle, of a sleeve fast thereon and having the upper 60 part of its exterior tapered upward for the support of a bobbin on that part only, and having below said tapered part an externally-cylindrical part larger than the tapered upper 65 part for the centering of the so-supported bobbin, substantially as herein described.

JOSEPH E. TYNAN.
